UNITED STATES PATENT OFFICE.

CURT B. MUELLER, OF CLEVELAND, OHIO.

TENNIS-RACKET.

971,773.

Specification of Letters Patent.

Patented Oct. 4, 1910.

Application filed October 5, 1909. Serial No. 521,047.

To all whom it may concern:

Be it known that I, CURT B. MUELLER, a citizen of the United States, resident of Cleveland, county of Cuyahoga, and State 5 of Ohio, have invented a new and useful Improvement in Tennis-Rackets, of which the following is a specification, the principle of the invention being herein explained and the best mode in which I have contemplated 10 applying that principle so as to distinguish it from other inventions.

My invention relates to tennis rackets, while more particularly to a new and improved manner of stringing the net in its 15 frame, and involving the use of reinforcing strings in a more efficient manner.

One of the features of a tennis racket, perhaps by general acknowledgment accredited primary importance, and certainly 20 that feature which contributes more toward its universal adaptability than any other, is its manner of net stringing. To meet the divers requirements, and in order to insure of absolute reliability and general effectiveness, the middle or most used portion of the 25 net should maintain a practically uniform, taut and standard-sized mesh at all times. Hence the demand arises for means especially devised to insure at one and the same 30 time these several essentials.

Heretofore reinforcing strings have been 35 patentably interwoven with the nets of tennis rackets in a number of different ways, the object of some of these patents having been to attain such a universal adaptability. However, in those actually effecting results 40 of comparative merit in the way of strings held more tightly and accordingly less likely to slip upon each other, such reinforcing strings have been strung through or near the middle, and accordingly resulted in a finer 45 mesh at the most used portion of the net. These systems of stringing a tennis racket, while effectually fulfilling one or both of the objects above suggested, have in the attainment thereof, done so at the cost of such a uniform and standard sized mesh at the middle or effective playing surface of the net. Thus a decidedly more prejudicial result, namely, an individually smaller and

less decided grip-of-contact upon the ball was substituted. Such a relatively smooth rebounding surface occasions a marked tendency of the ball to slip, and this is manifestly quite an appreciable factor of detriment in the many strokes whose effectiveness is directly and frequently wholly dependent upon the twist to be given the ball. 55

The object of this invention then, is to construct a tennis racket which, besides 60 embodying sundry practical and theoretical improvements to be pointed out, shall more certainly combine and effectively utilize all the various and well-recognized advantages 65 of reinforcing strings, and yet be entirely free from any accompanying disadvantages outweighing in relative importance any advantages heretofore attained.

The said invention consists of certain means which are hereinafter fully described 70 and particularly set forth in the claims.

The annexed drawings and the following description set forth in detail one mode of carrying out the invention, the disclosed mode, however, constituting but one of 75 various ways in which the principle of the invention may be applied.

In said annexed drawing:—Figure 1 is a face view of a tennis racket having the net strung in accordance with the principles of 80 this invention, the main part of the handle being shown as broken away. Fig. 2 is a like view of a variation of my invention, some of the features being omitted. Fig. 3 is a like view of a second variation, bearing 85 a different relation to the frame. Fig. 4 is an enlarged view more clearly showing the method of looping certain reinforcing strings adjacent to one corner of the frame. Fig. 5 is a similar enlarged view at an ad- 90 joining corner.

Referring to the drawing, in which like letters and numerals of reference designate like parts throughout the several views, the letter A is applied to so much of the handle 95 as is shown. The curved frame B is secured to this handle on either side, in the usual or any other approved manner, is preferably slightly thickened at the corners b' , b^2 , b^3 and b^4 , as drawn, and incloses any desired 100

form of wedge C, adjacent to said handle. A net composed of longitudinally extending strings D and laterally extending strings E is strung within the frame B through openings, not shown, since the method of looping the strings through the frame is well known. This net has a number of longitudinally extending strings d' , adjacent to said frame on each side, strung closer and preferably twice as closely as the normal longitudinal spacing of the remainder of these strings. Likewise a number of laterally extending strings e' adjacent to the tip B' and wedge C respectively, are strung closer and preferably twice as closely as the normal lateral spacing of the remainder of these strings. The number of more closely woven strings should preferably be such that the ones most remotely adjacent to each face of the frame shall intersect to form a nearly maximum sized rectangle, the corners of which are non-contiguous to the frame, it being desirable to have the normal mesh as extensive as possible within the scope of this invention. It will be manifest that this closer stringing adjacent the four sides of the frame may be effected either by continuations of the same strings or by separate unconnected strings. With such an inwardly extent for the more closely woven strings, a doubly fine resulting mesh will be formed at the central sections of the corners b' , b^2 , b^3 and b^4 , as will be easily seen in the drawing. These corners being the portions of the frame normally subjected to disproportionate strain, will accordingly be spared of any sudden concentrated shock, on the theory of the distribution of stress through a greater number of strings to a larger portion of the frame, and consonantly, the corners of the frame will be indirectly strengthened. The more closely woven lateral strings e' adjacent to the tip and wedge of said frame tend of themselves to tighten the longitudinal strings forming the standard sized mesh at the middle, and also, as a matter of course appreciably aid in preventing their lateral displacement by slipping. In the same way, the more closely woven longitudinally extending strings d' adjacent to the sides of said frame tend to both tighten and effectually secure the laterally extending strings forming standard-sized mesh at the middle against appreciable slipping. To illustrate in this connection the principle upon which the maintenance of a uniform mesh at the middle is assured, it will be apparent that the shorter the distance between the two points from which any string is strung with a certain degree of tightness, the less likelihood of any considerable stretch with resulting looseness and lateral give. In other words, the strings d' , e' , by making it more difficult for the strings D and E to slip on each other, serve

to maintain the uniformity of the mesh at the middle of the net. My improved reinforcing adaptation incidentally lends itself markedly as an added factor of resistance to the warping proclivity of the frame. As a further means, however, at once of tightening the strings, preventing their slipping, and serving to augment the area over which any strains occasioned when the ball strikes the net may be distributed, I provide an ancillary oblique stringing. This may likewise be accomplished either with connected or separate additional strings, and positioned in the net proper in any desired manner, providing the oblique strings do not pronouncedly intersect the boundaries of a nearly centrally disposed rectangle, to be composed of uniform and standard-sized mesh. In my preferred system, however, I employ two separate strings F and G, the same being interwoven with relation to my improved net in the following manner: Starting with one free end of the string G, as looped through two openings e' , in the central part of the exposed face of the wedge C, I interweave this end obliquely as far as the center of the particular mesh in the b' corner of the rectangle, then outwardly through the frame at b' , and back again along the frame, through another opening, then back to the center of the same mesh, then across the frame parallel with the strings E, as far as the center of the particular mesh in the b^4 corner, then obliquely to the middle of the frame, and out through the opening g' . Next I take the other free end of string G and interweave it obliquely from the opening e' in the wedge C to the center of the mesh in the b^4 corner, where it passes under, then over, the other free end previously passed through this mesh, then outwardly through the frame at b^4 , back again along said frame, and through the next opening, then obliquely back to the center of the same mesh over itself, but under the other free end, as best seen in Fig. 4, then across the frame in a direction parallel with strings D, as far as the center of the particular mesh in the b^3 corner, where after looping around string F it turns back to be finally interwoven obliquely again to meet with and be tied to its other end at the side of the frame. The second string F is strung in the same identical manner beginning with the two free ends from the tip B', and so as to loop around both parts of the string G in the b' corner, as clearly shown in Fig. 5, and in the same manner in which string G loops around both parts of string F in the b^3 corner. It will be understood that these strings F and G are interwoven in the net proper with the regular over and under weave. They are, moreover, with respect to their operative relation to the strings in

- the net proper absolutely independent, while their function is in so far identical with that of the reinforcing strings d' and e' that it is fulfilled either with or without the inclusion 5 of the latter.
- The modified form shown in Fig. 2 is merely simplified by the omission of the separate oblique strings F G, while the variation shown in Fig. 3 is a relative variation 10 with respect to the major axis of the frame, the standard uniform weave of the net being inclined at an angle in the drawing, and preferably at forty-five (45) degrees, with respect to said axis. The more closely 15 woven longitudinal and laterally extending strings with respect to the major axis of the frame and adjacent thereto are in this form preferably spaced apart half the diagonal distance of said standard mesh, so as to extend obliquely therethrough midway between the corners of said mesh. It will thus 20 be seen that this variation combines the two distinctive features of Figs. 1 and 2, in having a finer mesh surrounding a rectangle disposed on the major axis, such finer mesh being, however, formed by a series of strings 25 oblique with respect to the middle standard sized mesh.
- The provision of oblique strings to effect 30 a distribution and consequent lessening of stress at any given point is a well-known reinforcing expedient of mechanics. As applied, however, in conjunction with the usual right-angled weave in the net of a tennis 35 racket, or still further as combined with such a weave having a finer mesh contiguous to the sides of the frame, it presents an innovation in the art, and one calculated to increase not alone the durability, but also, 40 the efficiency.
- Having fully described my invention, what I claim therefore and desire to secure by Letters Patent is:
1. In a tennis racket, the combination of 45 a suitable frame, a net strung in said frame, and means comprising additional strings interiorly adjacent to, and connected with, the four sides of said frame, adapted to maintain the uniformity of the mesh in the middle, and effect the more even distribution of strains at the edges, of said net.
  2. In a tennis racket, the combination of 50 a suitable frame, a net strung in said frame, and means comprising a number of additional strings adjacent to each of the four sides, and intersecting at the corners, of said frame, adapted to maintain the uniformity of the mesh at the middle, and effect the more even distribution of strains at the edges, of said net.
  3. In a tennis racket, the combination of 55 a suitable frame, a net strung in said frame, having a number of its outwardly-located longitudinally-extending strings strung closer than the remaining longitudinally- 65 strung strings, and having a number of its outwardly-located laterally-extending strings strung closer than the remaining laterally-strung strings.
  4. In a tennis racket, the combination of 70 a suitable frame, a net strung in said frame, having a number of its outwardly-located longitudinally-extending strings strung closer than the remaining longitudinally- 75 strung strings, and having a number of its outwardly-located laterally-extending strings strung closer than the remaining laterally-strung strings, the inmost of said outwardly-located laterally and longitudinally-extending strings intersecting each other at right angles to form corner portions 80 of the net having smaller mesh than in any other part of the net.
  5. In a tennis racket, the combination with a frame, of a net strung in said frame, 85 said net having a number of oblique strings around its outer edge, and secured to the frame at a number of points.
  6. In a tennis racket, the combination with a frame, of a net strung in said frame, 90 and including a plurality of oblique strings adjacent, and secured, to said frame.
  7. In a tennis racket, the combination with a frame, of a net strung in said frame, 95 said net including oblique strings adjacent to, and secured to the middle of the four sides and corners of, said frame.
  8. In a tennis racket, the combination of 100 a suitable frame, a net strung in said frame, and a plurality of additional strings forming a rectangle and extending outward from the corners of said rectangle, and secured to a number of points on said frame.
  9. In a tennis racket, the combination of 105 a frame, a net strung in said frame, a plurality of strings looped about said frame and around each other to form four outwardly positioned triangles whose connected inner sides form a longitudinally disposed rectangle.
  10. In a tennis racket, the combination with a frame strung with a net of right-angled mesh; of two strings interwoven adjacent to said frame and obliquely relative to said mesh to form four outwardly positioned triangles whose apexes loop about the four sides and corners of the frame, whose inner sides loop about each other to form a longitudinally disposed rectangle.
  11. In a tennis racket, the combination of 115 120 a suitable frame, a net strung in said frame, having a number of its outwardly-located longitudinally-extending strings woven closer, and having a number of its outwardly-located laterally-extending strings woven closer, the innermost of said more closely woven strings intersecting each other at right angles to form a longitudinally dis-

posed rectangle of larger mesh, and a number of additional strings woven obliquely between said rectangle and frame.

12. In a tennis racket, the combination of
5 a suitable frame, a net strung in said frame,
and a number of strings looped through said
frame and around each other, to form four
outwardly positioned triangles whose con-
nected inner sides form a longitudinally dis-
10 posed rectangle, the laterally and longitudi-

nally extending strings of said net, outwardly located relative to said rectangle, being strung closer than the remaining laterally and longitudinally extending strings.

Signed by me, this 4th day of October, 15
1909.
